(57) **CLAIM**

The ornamental design for a faucet, as shown and described.

DESCRIPTION

FIG. 1 is a right, top, front perspective view of a faucet embodying my new design;

FIG. 2 is a top plan view thereof;

FIG. 3 is a front elevational view thereof;

FIG. 4 is a right side elevational view thereof, the left side elevational view being a mirror image of the right side shown;

FIG. 5 is a rear elevational view thereof; and,

FIG. 6 is a bottom plan view thereof.

The broken line representations of holes in FIGS. 1, 2, and 6 are for the purposes of illustration only, and form no part of the claimed design.
